IRONING CORD HOLDER

Marcus James Henry Bruce, London, England

Application December 20, 1949, Serial No. 6,738

Term of patent 14 years

(Cl. D49—1)

To all whom it may concern:

Be it known that I, Marcus James Henry Bruce, a subject of the King of Great Britain, Northern Ireland, and the Isle of Man, residing at 257 Kensington Close, Wright's Lane, London, W. 8, England, have invented a new, original, and ornamental Design for an Ironing Cord Holder, of which the following is a specification, reference being had to the accompanying drawing, forming part thereof.

Fig. 1 is a front perspective view of an ironing cord holder, showing my new design;

Fig. 2 is a rear perspective view; and

Fig. 3 is an enlarged sectional view thereof taken on line 3—3 of Fig. 1.

I claim:

The ornamental design for an ironing cord holder, as shown.

MARCUS JAMES HENRY BRUCE.
